A. DE BARBIERI

CATAPULT

Filed Sept. 26, 1922

FIG 1

FIG. 2

INVENTOR
A. De Barbieri

BY
Howard A. Division
ATTORNEY.

UNITED STATES PATENT OFFICE.

ANGELO DE BARBIERI, OF SYRACUSE, NEW YORK.

CATAPULT.

Application filed September 26, 1922. Serial No. 590,618.

To all whom it may concern:

Be it known that I, ANGELO DE BARBIERI, of Syracuse, in the county of Onondaga, in the State of New York, have invented 5 new and useful Improvements in Catapults, of which the following, taken in connection with the accompanying drawings, is a full, clear, and exact description.

This invention relates to a catapult for 10 throwing glass balls and other fragile objects commonly used as targets in trap shooting although it may be useful in the operation of valves, dampers, semaphores and analogous uses.

15 The main object is to provide a simple yet powerful device of this character in which the movable member is operated by coiled springs concentric with its axis of movement and normally held against the action of the 20 spring by a suitable locking device which may be electro-magnetically released by the use of a very small amount of current.

Another object is to provide means operable at will for restoring the movable member to its locked position from a point 25 remote from the device and at the same time to utilize the restoring means when actuated by said movable member when released for operating a semaphore or other signal 30 to indicate at a distant station that the movable member is in its discharged position.

Other objects and uses relating to specific 35 parts of the device will be brought out in the following description:

In the drawings, Fig. 1 is a top plan of 40 a catapult embodying various features of my invention with the spring actuated member in its locked position. Fig. 2 is a longitudinal, vertical sectional view of the same device showing the means for restoring the 45 movable member to its locked position after it has been released to throw the ball.

As illustrated, this device comprises a stationary supporting base or platform 1, 45 a spring actuated carrier 2 hinged at 3 to one end of the base 1 and actuated by a pair of coiled springs 4 which surround the pivotal pins 3 and are therefore, coaxial therewith, and a suitable lock 5 also mounted on the base and containing an electro-magnet 6 and an

armature 7 for holding and releasing the spring actuated member 2.

The base 1 may be secured by any suitable fastening means to a stationary support not shown and is provided with a stop arm 8 projecting from the under side into the path of movement of the platform when the latter is actuated by the action of the springs 4 through an arc of approximately 180°, or from its locked position directly over the base 1 to a position at one end of and in approximately the same plane as the base.

The movable section 2 normally extends from the hinge pins 3 to a point in proximity to the adjacent end of the lock 5 and is provided in its normal upper side with a shallow pocket 9 for receiving a ball a or other article to be thrown, the rear end wall of said pocket being of greater height than the remaining walls to form a resistance rib 10 having a downwardly and forwardly inclining front face 11 extending to the bottom of the pocket so that when the member 2 is released from its locked position the inertia of the ball combined with the momentum of the member 2 will cause the ball to be thrown forwardly and upwardly to a considerable height as a target for shooting, during which operation the member 2 will be brought to a stop against the free end of the stop member 8.

Suitable means may be provided for returning the member 2 to its locked position for repeating the operation just described and for this purpose is provided with a cable 12 which is passed around a sheave 13 on the under side of the base 1 and has one end attached to an arm 4 on the underside of the free end of the member 2, the other end of said cable being passed around a sheave 15 on a crank arm 16 of a semaphore signal 17 which may be pivoted at 18 to any available stationary support not shown, the free end of the cable being provided with an adjustable shoulder 19 and a handle 20.

The shoulder 19 is secured to the

cable at such distance as will permit the member —2— to swing from its locked position to engage the crank arm —16— just before the member —2— reaches its extreme open position for throwing the semiphore arm —17— upwardly to a substantially vertical position as shown by dotted lines Fig. 2 thereby indicating to the user that the trap or platform —1— is in its extreme open position whereupon, the trap may be returned to its locked position by simply drawing down upon the handle —20—.

During the opening movement of the trap —2— the end of the cable attached thereto, will of course, be drawn forwardly through an opening as —21— in the base —1— and in order that it may pass freely through said opening without excessive friction when the trap is open, I provided an extra sheave —22— journaled in the opening —21— just in front of the sheave —13— and upon which the cable is free to ride during the latter part of its opening movement and fore part of its closing movement.

The bracket —14— serves not only as a convenient means of attachment for the adjacent end of the cable —12— but also forms a stop or rest to limit the closing movement of the trap —2— by engaging the upper face of the base —1— as shown in Fig. 2.

The free end of the trap —2— is provided with a socket —23— for receiving a metal sleeve —24— which is tightly fitted therein without turning or endwise displacement and serves to receive a lock bolt —25—, the latter being spring pressed toward the lock by a coil spring —26— within the sleeve for interlocking engagement with a movable locking member of said lock.

The lock —5— may be of any suitable construction capable of engaging and disengaging the locking bolt —25— for holding and releasing the trap —2— and also capable of being operated by electro-magnet, as —6—, for releasing said trap and for this purpose I have shown a locking member —27— pivoted at —28— to swing into and out of engagement with the bolt —25— and cooperating with another pivoted member —28— which, in turn, normally rests upon the armature —7— to normally hold the member —27— in locking engagement with the bolt —25—.

This member —29— is released from engagement with the armature —7— when the latter is drawn toward the electro-magnet by the energizing thereof which may be ac-

complished by closing a push button switch 60 as —30— of a dry battery circuit of one or more cells.

Operation.

When the trap is locked in the manner described and it is desired to throw the object as —a—, it is simply necessary to push the button —30— which energizes the electro-magnet —6— thereby attracting the armature —7— and releasing the locking members —27— and —29— whereupon the spring pressure exerted upon the trap —2— by the springs —4— causes the bolt —25— to trip the member —27— from its holding position thereby permitting the springs to throw 75 the trap from its closed to its open position and at the same time throwing the ball —a— or other object upwardly and forwardly to a considerable height and a considerable distance from the trap to be used for target practice. Pulling down upon the cord or cable —12— restores the trap —2— to its closed position ready for a repetition of the throwing operation, it being understood that as the trap reaches its closed position the locking bolt —25— will be forced inwardly 85 against the action of the spring —26— by contact with the inclined face of the locking member —27— whereupon it is forced under the same into locking engagement therewith.

I claim;

In a catapult of the character described, a stationary platform, a carrier hinged at one end to one end of the platform and spring-actuated from a horizontal position at one side of the hinge to a substantially horizontal position at the opposite side of the hinge, cooperative members on the platform and carrier normally holding the carrier in the first named position, each of said members being movable into and out of holding engagement with the other member, a stop-arm on the platform for limiting the movement of the carrier to the second-named position, and means for tripping one of said members to release the carrier from said first-named position, said stop-arm extending under the longitudinal center of the carrier when the latter is in the second-named position.

In witness whereof I have hereunto set my hand this 23d day of September, 1922.

ANGELO DE BARBIERI.
